DUPLICATING APPARATUS

Henry Kastriner, Cleveland, Ohio

Application November 9, 1931, Serial No. 573,835

3 Claims. (Cl. 101—118)

The present invention, relating as indicated to a duplicating apparatus, has more precise reference to a novel construction for a device for imprinting typewritten characters by means 5 of a stencil sheet.

It is a general object in the nature of my invention to provide an extremely simplified and efficient form of stencil duplicating machine which possesses several features of novelty over 10 such machines which have been heretofore employed for the same purpose.

It is a further object to provide a feed roller for the sheet to be printed which does not require the presence of springs or similar auxiliary 15 pressure means.

One object of my invention is to provide a means for introducing and discharging the stencilled sheets upon the same side of the apparatus so that it is not necessary for the operator 20 to be subjected to the additional effort of reaching from one side of the machine to the other.

It is a further object to provide a device of 25 relatively cheap and simple construction which may be operated by a person of average skill and intelligence.

Objects and advantages additional to those above enumerated shall become apparent during the following description:

To the accomplishment of the foregoing and 30 related ends, said invention, then consists of the means hereinafter fully described and particularly pointed out in the claims.

The annexed drawings and the following description set forth in detail certain mechanism 35 embodying the invention, such disclosed means constituting, however, but one of various mechanical forms in which the principle of the invention may be used.

In said annexed drawings:

40 Fig. 1 is a top plan view of the apparatus embodying the principle of my invention; Fig. 2 is a vertical section taken substantially upon line 2—2 of Fig. 1; Fig. 3 is a side elevational view of Fig. 1 and Fig. 4 is a vertical section 45 taken substantially upon line 4—4 of Fig. 1.

Referring more particularly to the drawings, the apparatus constructed in conformity to the principle of my invention possesses the rectangular base portion 1 upon which are secured 50 the vertical support frame members 2 and 3. A rotatable stencil drum 4, such as customarily used in similar machines is carried by the frame members at the bearing points 5 and 6. A crank arm 7, carrying the handle 8, is secured to 55 one end of the shaft of the rotatable drum 4

by means of a suitable wing nut 9. The drum 4 has the central hollow shaft 10 in the interior of which is inserted a smaller shaft 11 to which, in turn, is secured the smear brush 12. A pair of long screw bolts 13 and 14 threadably engage 5 with the shaft 11 and are for the purpose of adjusting the position of the smear brush 12 in relation to the interior of the drum 4. A handle 15 is secured to the outer end of the shaft 11 in order to manipulate the smear brush 12 around the interior of the drum 4 and to thoroughly distribute the inking medium 10 over the interior surface of the stencil.

A feeding tray 16 is removably supported at the point 17 to the frame members 2 and 3. 15 A supporting arm 18 further tends to hold the feeding tray 16 in place upon the frame. The feeding tray may thus be removably swung 20 out of position in order to facilitate access to the stencil drum 4 when it is found necessary 20 to change stencils. A pair of adjustable guides 19 and 20 are positioned upon the upper surface of the feeding tray 16 for the purpose of 25 accommodating blank sheets of paper of various widths.

In order to properly hold the sheet to be printed against the surface of the rotating stencil, I provide a relatively heavy solid metallic feed roller 21 having on each end the journals 22 and 23 which are adapted to fit into suitable 30 slots at the top edge of the vertical frame supports 2 and 3. For the purpose of facilitating the handling of the feed roller 21, the knurled 35 knob 24 may be provided on the end of the journal 23. For the purpose of returning the 35 printed sheets to the same side of the machine as that from which they were initially introduced, I provide the passage-way or chute 25 having the arcuate inner and outer walls 26 and 27 respectively. The curved outer wall 27 40 is integral with the angularly inclined straight portion 28, so that the printed sheets will be guided into the removable receiving tray 29.

For the purpose of imparting an intermittent 45 stopping motion to the rotation of the stencil drum, the spring-loaded plunger 30 on the end of the crank handle 8 is adapted to engage with the arcuate groove 31 in the spring bracket 32. As shown in Fig. 2, the arcuate groove 31 has a deeper hemispherical cavity 33 for the reception 50 of the spring-loaded plunger 30, so that the last described mechanism shall possess a detent action for the purpose of temporarily stopping the rotation of the drum 4 on each revolution.

It will thus be seen that when a blank sheet 55

of paper is placed in the feeding tray 16 and engaged by the stencil drum 4 and feed roller 21, that it is carried around the passage-way 25 and discharged into the receiving tray 29 with the printed surface uppermost. Accordingly, it is possible for the operator to have a full and complete view of each sheet immediately after it is printed. Furthermore, there are no complicated levers, springs or adjusting mechanisms which require the attention of a skilled operator.

It should be further noted that the crank handle connection 34 of the crank arm 7 to the drum shaft 5 is made serrated and adjustable in order that the starting position of the drum 4 may be made variable in relation to the starting position of the crank handle. The advantage of the last described feature resides in the fact that when the stencil becomes shortened because of cutting, tearing, or otherwise damaged and hence must undergo a relative change of position on the drum, it is merely necessary to change the starting position of the drum so that the position of the stenciled or printed matter on the paper sheet will be properly compensated for and placed.

It will thus be seen that the construction of the device embodying the principle of my invention possesses the further advantages in that the rotating drum is substantially completely enclosed, preventing catching and entanglement of the operator's clothing; and that the entire assembly occupies a relatively small space as compared to the structures of the prior art.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a stencil duplicating apparatus, the combination of a rotatable stencil drum, a stencil printing sheet carried by said drum, a sheet feeding tray positioned adjacent the upper circumference of said drum and having its inner end located substantially adjacent the vertical diameter of said drum, and a sheet receiving tray positioned below said feeding tray having

its outer end extending beyond the outer end of said feeding tray, and the inner end of said receiving tray being disposed below the bottom circumference of said drum and beyond a vertical line coincident with the periphery of said drum, whereby the interior of said receiving tray is accessible and visible by an operator from the same side of the apparatus as that on which said feeding tray is positioned.

2. In a stencil duplicating apparatus, the combination of a rotatable stencil drum, a stencil printing sheet carried by said drum, a removable sheet feeding tray positioned adjacent the upper circumference of said drum and having its inner end located substantially adjacent the vertical diameter of said drum, and a removable sheet receiving tray positioned below said feeding tray having its outer end extending beyond the outer end of said feeding tray, and the inner end of said receiving tray being disposed below the bottom circumference of said drum and beyond a vertical line coincident with the periphery of said drum, whereby the interior of said receiving tray is accessible and visible by an operator from the same side of the apparatus as that on which said feeding tray is positioned.

3. In a stencil duplicating apparatus, the combination of a rotatable stencil drum, a stencil printing sheet carried by said drum, a removable sheet feeding tray positioned adjacent the upper circumference of said drum and having its inner end located substantially adjacent the vertical diameter of said drum, and a removable sheet receiving tray positioned below said feeding tray having its outer end extending beyond the outer end of said feeding tray, and the inner end of said receiving tray being disposed below the bottom circumference of said drum and beyond a vertical line coincident with the periphery of said drum, whereby the interior of said receiving tray is accessible and visible by an operator from the same side of the apparatus as that on which said feeding tray is positioned, and a conveying chute leading from the side of said drum opposite to that of said feeding tray to the inner end of said receiving tray for directing the printed sheets from said drum to said receiving tray.

HENRY KASTRINER. 50
